ATTORNEY.

UNITED STATES PATENT OFFICE.

ALBERT WILLIAM SCHMID, OF BASEL, SWITZERLAND.

APPARATUS FOR TREATING SILK AND OTHER TEXTILE GOODS IN HANKS BY MEANS OF LIQUIDS.

1,277,136.

Specification of Letters Patent. Patented Aug. 27, 1918.

Application filed October 12, 1917. Serial No. 196,148.

To all whom it may concern:

Be it known that I, ALBERT WILLIAM SCHMID, a citizen of the Swiss Republic, and resident of Basel, Switzerland, have invented new and useful Improvements in Apparatus for Treating Silk and other Textile Goods in Hanks by Means of Liquids, of which the following is a full, clear, and exact specification.

10 In the dyeing of silk and other textiles in hanks it is already known to suspend these hanks on reels with a horizontal, eccentric axis of revolution so that upon the turning of these reels the hanks will receive motions favorable to the dyeing or other treatment of the goods, namely a to-and-fro motion and a moving about in the dye bath or a similar treating bath. Moreover in apparatus for the treating of silk hanks with 20 soap foam, reels with central driving shafts are known which reels are so arranged raisably that they facilitate when raised the insertion or removal of the hanks.

The present invention relates to an apparatus for the treatment of textile goods in the form of hanks with liquids in which, on the one hand the to-and-fro movement and moving about of the goods in the treating liquid is effected in the well-known manner by the rotation of reels serving as hank supports provided with eccentric shafts of rotation, while on the other hand the eccentric shaft of rotation of each such reel, instead of being held fast in the horizontal 30 position as hitherto, is so supported pivotally that the reel can be brought to such a raised position, that by this means the hanks suspended from it can be raised entirely out of the liquid bath.

40 In each reel, the pivotal point of the bearing which holds one end of the eccentric reel shaft is arranged at such a distance from the reel that in the raised position thereof the hanks are completely out of the bath.

45 Moreover, the raising of the separate reels when charged with hanks can be facilitated by the arrangement, that the aforesaid bearing of the eccentric reel shaft has an extension beyond the aforesaid pivotal point and is provided there with a counter-balance weight.

Furthermore, the aforesaid bearing may be provided with a hook which upon the 55 raising of the reel can be engaged with a

second hook pivoted to the machine frame. The aforesaid bearing can moreover be provided with a pushing finger which is so arranged in relation to a releasing lever for the hook pivoted to the machine frame, that, 60 when the reel is raised somewhat above the elevated position in which the two hooks engage one another, the said finger displaces the releasing lever, and thereby releases the hook pivoted to the machine frame from the 65 other hook to allow of subsequent lowering of the reel.

In the accompanying drawing is illustrated a constructional example of the invention in sectional elevation.

70 In this drawing A indicates a fixed dye vat, above which is placed the reel B with its rotating shaft C arranged eccentric to it, so that the hanks suspended from the reel B dip into the liquid in the vat, and on 75 the rotation of the reel B around the longitudinal axis of its eccentric shaft perform the usual to-and-fro motion and moving about in the dye bath. The shaft C of the reel B bears a worm wheel a which when 80 the shaft C is in the horizontal position engages with the worm b, and the one pivot of this shaft C rests in a bearing E removably supported in the machine frame D, while the other pivot is supported in a bearing F pivoted at c to the machine frame D, and provided on the one hand with a prolongation e carrying a counter-balance weight d and on the other hand a hook f 85 with a pushing finger g.

To the machine frame D there is further pivoted a second hook h in the form of a lever, and also underneath this latter a releasing lever i which rests against the lower arm of the hook h. The machine can obviously 90 be fitted with a larger or smaller number of such reels, the driving worms of which are placed upon a common shaft and which correspond to one or more dye vats.

95 During the dyeing the reels are in the 100 horizontal position shown in the drawing and these reels are actuated in the well known manner by their eccentric shafts C, so that they effect the to-and-fro motion and the turning about of the hanks suspended 105 from them in the dye bath. If the hanks on any particular reel have to be lifted out of the corresponding bath, it suffices to raise the reel at its free end so that it turns together with its shaft C and the bearings E 110

and F therefor around the pivot *c* of the bearing F. By this means all the hanks suspended from the reel are raised completely out of the dye bath, provided that the distance between the pivot *c* and the rear end of the reel is large enough; in other cases the lower part of the hanks can conveniently be turned back to bring the hanks completely out of the bath. As soon as the reel when being raised reaches its highest position, the hook *f* engages with the hook *h* so that the frame is held in this elevated position and the desired manipulations of the bath can be undertaken. When it is desired to let down the reel again, it is first lifted somewhat above the normal high position, so that the finger *g* strikes against the lower arm of the releasing lever *i* and thereby releases the hook *h* from the hook *f*. The reel is then allowed to descend quickly so as to immediately bring the hook *f* out of reach of the hook *h*.

What I claim is:

1. In an apparatus for the treating of silk and other textiles in the form of hanks with liquids, the combination with a treatment vessel of a normally horizontal hank support, an eccentric rotary shaft carrying said hank support, a bearing for said shaft pivotally mounted at such a distance from the hank support that when the latter is raised, the hanks suspended from it are automatically lifted quite above the liquid in the vessel, and a worm gear placed between the pivotal point of said bearing and the hank support for imparting a rotary motion to the said shaft and arranged so as to allow the pivotal raising of the hank support, substantially as described.
2. In an apparatus for the treating of silk and other textiles in the form of hanks with liquids, the combination with a treatment vessel of a normally horizontal hank support, an eccentric rotary shaft carrying said hank support, a bearing for said shaft pivotally mounted at such a distance from the hank support that when the latter is raised, the hanks suspended from it are automatically lifted quite above the liquid in the vessel, and a worm gear placed between the pivotal point of said bearing and the hank support for imparting a rotary motion to the said shaft and arranged so as to allow the pivotal raising of the hank support, the said bearing being prolonged beyond its pivotal point and being provided with a counter-balance weight in order to facilitate the raising of the hank support, substantially as described.
3. In an apparatus for the treating of silk and other textiles in the form of hanks with liquids, the combination with a treat-

ment vessel of a normally horizontal hank support, an eccentric rotary shaft carrying said hank support, a bearing for said shaft pivotally mounted at such a distance from the hank support that when the latter is raised, the hanks suspended from it are automatically lifted quite above the liquid in the vessel, and a worm gear placed between the pivotal point of said bearing and the hank support for imparting a rotary motion to the said shaft and arranged so as to allow the pivotal raising of the hank support, the said bearing being provided with a counter-balance weight in order to facilitate the raising of the hank support and with a hook, a second hook being supported on the machine frame in such a position that on the lifting of the hank support the first hook can engage with the second hook for the purpose of holding the hank support in its raised position, substantially as described.

4. In an apparatus for the treating of silk and other textiles in the form of hanks with liquids, the combination with a treatment vessel of a normally horizontal hank support, an eccentric rotary shaft carrying said hank support, a bearing for said shaft pivotally mounted at such a distance from the hank support that when the latter is raised, the hanks suspended from it are automatically lifted quite above the liquid in the vessel, and a worm gear placed between the pivotal point of said bearing and the hank support for imparting a rotary motion to the hank support, the said bearing being provided with a counter-balance weight in order to facilitate the raising of the hank support and with a hook, a second hook being supported on the machine frame in such a position that on the lifting of the hank support the first hook can engage with the second hook for the purpose of holding the hank support in its raised position, the said second hook being combined with a releasing lever and the said bearing being also provided with a push finger so arranged with regard to the said releasing lever that, when the hank support is raised a little above the position in which the two hooks mutually engage, the push finger displaces the releasing lever and releases thereby the hook supported on the machine frame from the other hook, to allow of lowering of the hank support, substantially as described.

In witness whereof I have hereunto signed my name this 1st day of September, 1917, in the presence of two subscribing witnesses.

ALBERT WILLIAM SCHMID.
